UNITED STATES PATENT OFFICE.

EDWARD D. HARE, OF ERIE, PENNSYLVANIA.

DEVICE FOR CLEANING JEWELRY.

Application filed October 8, 1925. Serial No. 60,277.

This invention relates to a device for cleaning rings and other jewelry and the object thereof is to provide a receptacle to contain cleaning material, and means adapted to be inserted therein to suspend rings in the receptacle, so that the receptacle can be shaken, and thereby agitate the contents, and thereby clean the rings.

The features of my invention are herein after fully described and pointed out and are illustrated in the accompanying drawing in which:

The figure is a central vertical section of a receptacle embodying my invention.

In the drawing A indicates a receptacle made preferably of glass provided with an internal annular shoulder B adjacent to the upper end thereof, and is provided with a suitable cork for closing the upper end thereof. Resting on the shoulder B is a metallic bar D in which are secured posts E, provided with heads on their lower ends. Slidably mounted on said posts is a metallic bar F, and between the bar F, and bar D upon said posts E are springs G which press the bar F away from the bar D, the heads on the lower ends of the posts E retaining the bar F on said posts.

Stick pins can be inserted into the cork C

so that they will project into the receptacle 30 and be suspended therein while being cleaned.

In operation the bars D and F are lifted out of the receptacle, and pressed together by compressing the springs G, and rings desired to be cleaned are slipped onto said bars, and the bar F is released so that the bars spread apart, thereby holding the rings steady, while the cleansing fluid in the receptacle A is agitated.

Having thus fully shown and described my invention so that others can utilize the same, what I claim as new and desire to secure by Letters Patent is:

A receptacle, an annular shoulder within 45 said receptacle, a transverse bar resting upon said shoulder, downwardly extending spaced posts secured in said bar, a transverse bar 50 slidably mounted on said posts, heads on said posts to prevent said last mentioned bar from falling off of said posts, springs on 55 said posts between said transverse bars, and a cork to close said receptacle and maintain said first mentioned bar down upon said shoulder.

In testimony whereof I affix my signature.

EDWARD D. HARE.
